UNITED STATES PATENT OFFICE.

EDGAR E. HENDRICKSON, OF HOPKINSVILLE, KENTUCKY.

BALL-RACE EXTRACTOR.

Application filed April 9, 1925. Serial No. 21,948.

This invention relates to ball race extractors and more particularly to a device for extracting the outer races of ball bearings from the mountings thereof.

An important object of the invention is to provide a device of this character which will remove the race without marring the same, which may be readily and cheaply constructed and which will be durable and efficient in service.

These and other objects I attain by the construction shown in the accompanying drawings, wherein for the purpose of illustration is shown a preferred embodiment of my invention and wherein:—

Figure 1 is a vertical sectional view through a ball race extractor constructed in accordance with my invention applied to remove a ball race from the housing thereof; Figure 2 is a view of the extractor removed, the outer shell being shown in section;

Figure 3 is a top plan view of the shell; Figure 4 is a bottom plan view of the complete extractor; and

Figure 5 is a top plan view of the inner element of the extractor.

Referring now more particularly to the drawings, the extractor comprises an outer shell 10 of a proper diameter for engagement with the housing H of the ball race. This shell has a reduced interiorly screw-threaded hollow neck 11, the exterior face of which is provided with flats 12 for engagement in a wrench or vise. Arranged within this shell and threaded into the neck thereof is an extractor or pulling plunger having a body portion threaded intermediate its ends, as at 13, for coaction with the threads of the neck 11. At one end, the body portion is longitudinally slit, at diametrically opposed points 14, to provide a plurality of expansible or contractible arms 15. In order that the expansion and con-

traction of the arms may be readily accomplished, the connection of these arms with the body is weakened by enlarging the slits 14 at the inner ends thereof, as indicated at 16. These arms are each provided upon the outer face thereof with a circumferentially extending bead 17, the beads of the arms combining to form an annular flange which is of the same size as the race groove G of the race R which is to be removed.

The opposite end of the body is provided with wrench flats 18 for coaction with either

a wrench or vise as may be desired. Through the body is formed a longitudinally extending bore 19, that portion of the bore lying between the arms 15 tapering and increasing in diameter toward the free ends of the arms, as more clearly shown at 20. Directed through the bore 19 of the extractor is a shank 21 of the same size as the bore having at one end a tapered enlargement 22 corresponding to the taper at 20 of the bore 19 and having at its opposite end screw-threads 23 for coaction with a wing nut 24. This shank is of greater length than the body so that the wing nut 70 engaged with the threads thereof may seat upon the end of the body of the extractor while the tapered portion may be extended beyond the free ends of the arms so that these arms may converge and reduce the 75 external diameter thereof, particularly at the bead 17.

In the use of the device, while these arms are converged, the extractor is pushed into the bore B of the race until the beads 17 engage in the race groove G. The shell 11 is then engaged and shifted until it seats against the housing of the bearing about the race. The wing nut is then applied and screwed home until the wedge has spread 80 the arms 15 a desired distance and the extractor is no longer withdrawable from the race R. The outer shell 11 is then held against movement by a wrench or vise while the extractor is rotated to withdraw the 85 race from its housing. The housing may be of any character, it being merely necessary that the shell 10 have a diameter slightly greater than the bearing and less than the external diameter of the housing and a depth 90 greater than the depth of the race which is to be extracted. In the present instance, the housing H is illustrated as the housing provided upon the end bearings of small 95 motors.

Since the construction of the device is obviously capable of a considerable range of change and modification without materially departing from the spirit of my invention. I do not limit myself to such specific structure except as hereinafter claimed.

I claim:—

In an extractor for the outer races of ball bearings, a shell having an interiorly threaded neck, an extractor threaded 110 through the neck and formed at one end with arms, each provided upon the outer

face with a bead for engagement in the ball race groove of the race to be extracted, said extractor having a longitudinal bore tapered at that end thereof lying between the 5 arms with a taper increasing in size toward the ends of the arms, and a wedge shiftable through the bore and engaging said taper for expanding the arms, the end of the ex-

tractor being longitudinally split to provide said arms, the inner ends of the splits being enlarged to add to the resiliency of the arms at the inner ends thereof. 10

In testimony whereof I hereunto affix my signature.

EDGAR E. HENDRICKSON.
